UNITED STATES PATENT OFFICE.

BÉLA RAJNER, OF BUDAPEST, AUSTRIA-HUNGARY.

CONVERTIBLE FURNITURE.

No. 863,874.

Specification of Letters Patent.

Patented Aug. 20, 1907.

Application filed July 9, 1906. Serial No. 325,274.

To all whom it may concern:

Be it known that I, BÉLA RAJNER, a subject of the King of Hungary, and a resident of Budapest, in the Kingdom of Hungary, have invented certain new 5 and useful Improvements Relating to Convertible Furniture, of which the following is a specification.

The present invention relates to a chair or seat, such as a sofa or an arm-chair, which is convertible into a bed. Its object is to provide an article of furniture, 10 cheap and simple in construction, which may be speedily converted into a bed.

A seat frame carries a seat and projects at its ends beyond the seat. Vertically disposed arms are detachably connected to the projecting ends of the seat 15 frame, one or more of said side arms being adapted to be detached and connected to the end portions of said seat frame in a horizontal position to form a continuation thereof. A detachable back is connected to the seat between the arms and is adapted to overlie the 20 projecting ends of the seat frame and the continuations, when detached.

The invention is illustrated in the accompanying drawings, in which Figure 1 represents a sofa, constructed according to the present invention, Fig. 2 shows 25 the same converted into a bed. Fig. 3 is a perspective view of an arm chair, and Fig. 4 a view similar to Fig. 2. Fig. 5 shows a detail of construction.

The seat frame *d* is supported by legs or standards and carries a seat *k*. The ends of this frame project 30 beyond the seat *k* and are provided with slots *c'*, *c'*. Vertically disposed arms *a* and *b* are detachably connected to said projecting ends of the seat frame *k* by means of wooden tenons *l*, fitted into the slots *c'*, *c'*, formed in the projecting ends of the frame *d*. In order 35 to permit of converting the seat into a bed, slots *c*, *c* are provided on the vertical ends of the frame *d*, and are

adapted to receive the tenons *l* when the arms are brought into the horizontal position. On the front and rear ends of the arms *a* and *b* legs *e*, *e* are arranged. These legs support the arms *a* and *b* in the horizontal 40 position. Hooks *j*, *j* are provided for securing the arms *a* and *b* to the frame, when in the horizontal and vertical position. The difference of level, which exists between one of the two arms turned down in this manner and the seat *k*, is compensated by the back cushions *f* 45 and *g*, and if necessary by the reserve cushion *h*. To attain this end, it is necessary that, in the form shown in Fig. 1, the thickness of the back cushions should be exactly half of the thickness of the seat *k*, and their length should be the sum of the height of the arm *a* or *b* and the length of the projection of the frame *d*. 50

The dimensions of the chair, illustrated in Figs. 3 and 4 should be as follows: the thickness of the reserve cushion *h* and the back cushion *f* should correspond to the thickness of the seat *k*, and the length again the 55 sum of the height of the arms *a* or *b* and the length of the projection of the seat frame.

As new and useful is claimed and desired to be secured by Letters Patent of the United States:—

In a convertible chair, a seat frame, a seat carried 60 thereby, the said seat frame at its ends projecting beyond the seat, vertically disposed arms detachably connected to the projecting ends of the seat frame, a back detachably connected to the seat frame between the said arms, one of said arms adapted to be detached and 65 connected to the end portion of the seat frame in a horizontal position to form a continuation thereof, the back when detached adapted to overlie the said projecting ends of the seat frame and the said continuation.

Signed at Budapest, in the Kingdom of Hungary this 70
16th day of June A. D. 1906.

BÉLA RAJNER.
